(57) **CLAIM**

The ornamental design for a glass block spacer, substantially as shown and described.

DESCRIPTION

FIG. 1 is a front perspective view of the glass block spacer showing my design in use;

FIG. 2 is a fragmentary perspective view of the glass block spacer of my design;

FIG. 3 is a front elevational view thereof on an enlarged scale;

FIG. 4 is a rear elevational view thereof on an enlarged scale;

FIG. 5 is a fragmentary right side elevational view thereof on an enlarged scale;

FIG. 6 is a fragmentary left side elevational view thereof on an enlarged scale;

FIG. 7 is a fragmentary top plan view thereof on an enlarged scale; and,

FIG. 8 is a fragmentary bottom plan view thereof on an enlarged scale.

The broken lines showing environment in the drawings are for illustrative purposes only and form no part of the claimed design.
